CONTAINER FOR PAINT OR THE LIKE

Howard B. Pashman, 74 Lake Shore Drive,
Eastchester, N.Y. 10709

Filed Mar. 25, 1968, Ser. No. 11,128

Term of patent 14 years

Int. Cl. D9—07

U.S. Cl. D9—239

FIG. 1 is a top plan view of a container for paint or the like, showing my new design;

FIG. 2 is a side elevational view thereof;

FIG. 3 is bottom plan view thereof; and

FIG. 4 is a vertical section on the line 4—4 of FIG. 1, double size.

I claim:

The ornamental design for a container for paint or the like, as shown.
